FLYING MACHINE

John F. Boettner, Watson, Mo.

Application April 27, 1936, Serial No. 76,688

1 Claim. (Cl. 244—80)

The present invention relates to new and useful improvements in flying machines of the heavier than air type and has for one of its important objects to provide, in a manner as hereinafter set forth, a machine of this character which is wingless or substantially so and which depends for its lift and propulsion on a plurality of propellers or air screws which are driven directly from outboard motors, said motors, with the propellers, being rotatably adjustable to any desired angle for ascent, descent and for forward movement.

Another important object of the invention is to provide a flying machine of the aforementioned character in which the usual landing gear is dispensed with, the motors, when turned to a vertical position, constituting supports for the machine.

Still another important object of the invention is to provide a flying machine of the character described comprising a plurality of motors, together with novel means for synchronizing said motors.

Other objects of the invention are to provide a flying machine of the character described which will be comparatively simple in construction, strong, durable, efficient and reliable in operation, compact and which may be manufactured at low cost.

All of the foregoing and still further objects and advantages of the invention will become apparent from a study of the following specification, taken in connection with the accompanying drawings wherein like characters of reference designate corresponding parts throughout the several views and wherein:—

Figure 1 is a top plan view of a flying machine constructed in accordance with the present invention.

Figure 2 is a view in side elevation thereof.

Figure 3 is a fragmentary view in vertical longitudinal section through an intermediate portion of the fuselage, showing the means for rotating the motors.

Figure 4 is a fragmentary view in vertical transverse section taken substantially on the line 4—4 of Figure 1.

Figure 5 is a diagrammatic view of the motor controlling system.

Figure 6 is a detail view in horizontal section through one of the fluid pressure responsive motor control units, taken substantially on the line 6—6 of Figure 7.

Figure 7 is a detail view in side elevation of one of the motor control units.

Referring now to the drawings in detail, it will be seen that the embodiment of the invention which has been illustrated comprises a fuselage 1 of any suitable size, shape and material. Mounted transversely in the front and rear end portions of the fuselage 1 and projecting therefrom are tubular shafts 2 and 3 which are journaled in bearings 4. Fixed on the outer ends of the shafts 2 and 3 are motors 5 which drive the propellers 6.

Fixed on the shaft 2 is a hand lever 7 which is connected by the rod 8 with an arm 9 which is fixed on the shaft 3. The rod 8 is slideable in guides 10 which, in the arrangement illustrated, depend from the floor 11 of the fuselage 1. The hand lever 7 is operable in a slot 12 which is provided therefor in the fuselage floor 11. Any suitable means, as at 13, may be provided for releasably securing the hand lever 7 in adjusted position.

It will thus be seen that through the medium of a single lever 7 all of the motors 5 may be rotatably adjusted as desired in unison. With the motors 5 in vertical position, as suggested in dotted lines in Figure 2 of the drawings, said motors constitute a support or landing gear for the machine. With the motors 5 in this vertical position the machine may be caused to ascend and descend vertically. When the desired altitude has been reached the motors 5 are swung toward a substantially horizontal position for pulling the machine forwardly. By properly regulating the motors 5 the machine may be caused to hover in the air. The motors 5 are properly balanced on the shafts 2 for ease of operation.

The fuselage 1 may be provided with a suitable arrangement of windows 14, a door 15, etc. The reference numeral 16 designates windows for the pilot. Also, the fuselage 1 may have formed in its upper portion a chamber 17 for the reception of helium or any other suitable buoyant gas. On the rear end of the fuselage 1 is a tail assembly which is designated generally by the reference numeral 18 and which may be operated by any suitable means by the pilot.

Referring now to Figure 5 of the drawings, it will be seen that a foot accelerator 19 is connected by cables or the like 20 to the arms 21 of the throttle valves of the carburetors of the motors 5. Springs 22 yieldingly urge the throttle valves toward closed position.

The reference numeral 23 designates generally automatic motor control units with which each motor 5 is provided. The units 23 comprise ex-

5   pansible balls 24 for the reception of a suitable fluid 25 (see Figure 6), said balls 24 communicating with each other through conduits 26. At intermediate points, the cables 20 are formed to provide loops or bridles 28 which pass slidably through guides 29 on opposite sides of the balls 24. It will thus be seen that should the craft 10 tilt from a horizontal plane while in flight, the fluid 25 will immediately flow by gravity into the lowermost ball 24 and expand same in a manner to increase the speed of that motor and bring the craft to a horizontal position.

10   It is believed that the many advantages of a flying machine constructed in accordance with the present invention will be readily understood and although a preferred embodiment of said machine is as illustrated and described, it is to be understood that changes in the details of construction and in the combination and arrange-

ment of parts may be resorted to which will fall within the scope of the invention as claimed.

What is claimed is:

A flying machine of the class described, comprising a fuselage, a plurality of motors 5 mounted on said fuselage, propellers driven by said motors, common means for manually controlling the motors and gravity responsive means for controlling said motors, the last named means including expansible and contractible balls for the 10 reception of a fluid, conduits connecting said balls, one of said balls being associated with each motor, and cables operatively connected to the throttle valves of the motors and operatively connected to said balls for actuation thereby in accordance with deviations in the balance of the 15 machine.

JOHN F. BOETTNER.
